UNITED STATES PATENT OFFICE

JOHN C. SHAMBOW, OF SALEM, NEW HAMPSHIRE, ASSIGNOR TO UNITED SHOE MANUFACTURING CORPORATION, OF PATERSON, NEW JERSEY, A CORPORATION OF NEW JERSEY

WOOD HEEL CONCAVING MACHINE

Application filed April 14, 1930. Serial No. 444,165.

This invention relates to machines for concaving heels and is illustrated as embodied in a so-called hand-concaving machine.

A wood heel concaving machine has for its object to form the concave attaching surface on the wood heel. Many such heels, as now manufactured, are required to have a flat rim of even width around the sides and back of the attaching surface. Concaving machines of the type mentioned have a rotary cutter projecting through a slot in a flat table with an adjustable straight gage running perpendicularly to the slot. The heel blank is placed upside down on the table and pushed and turned over the cutter by hand. The movement of the heel blank at the point of cut is sidewise of the cutter, and the edge of the attaching face of the blank is kept against the gage directly opposite the cutter. In order to prevent dragging the blank out of the operator's fingers the cutter rotates toward the gage, thus tending to push the blank toward the gage and to crowd it down on the table.

This has resulted in the spoiling of much work due to the cutter tearing out pieces of the narrow thin rim of the attaching surface, which passes over the slot, past the cutter, without adequate support. This difficulty is increased by the fact that the grain of the wood runs longitudinally in a heel blank, and little pieces of the rim are very easily split off.

A principal object of the present invention is to avoid this difficulty. To this end I have provided a supporting plate closely surrounding the operative portion of the cutter, to support the rim at points immediately adjacent to the cutter teeth. This guard plate is made of material, preferably such as fiber or brass, which is rigid but substantially softer than the cutter, and is movable along the work table so that the cutter can cut its own way into it and secure a perfect fit between the cutter and the guard plate, irrespective of the shape of cutter being used for the particular work in hand.

In accordance with a feature of the invention the guard plate is located in a groove in the top of the work table and is held therein

in operative position by the gage. It is thus steadied in its movement toward the cutter, when being set to fit a new cutter, by the gage. This results in a simple and easily operable construction.

I have also provided a convenient and efficient means of adjusting the table. It is necessary to use cutters of varying diameters, and to have the cutters project above the table by different amounts in case of different kinds of work. Therefore, in the illustrated machine, I have provided a vertical adjustment for the table, and have combined therewith a pivotal adjustment about a horizontal axis (both of these adjustments being relatively to the cutter) so that the table can always be placed at a convenient angle for the operator and at the same time at the proper height relatively to the cutter.

These and other features of the invention comprising certain combinations and arrangements of parts will be apparent from the following description of a preferred embodiment of the invention shown in the drawings.

Fig. 1 is a perspective view of the machine;

Fig. 2 is a transverse section perpendicular to the axis of the cutter;

Fig. 3 is a section on the line III—III of Fig. 2;

Figs. 4 to 8 are details showing successive stages of the operation of concaving a heel blank;

Figs. 9 and 10 illustrate heel blanks before and after concaving, respectively.

The main frame 10 is provided with a vertical slideway 12 in which slides a block 14. The block 14 is adjustable in the slideway by a screw 16 with a lock nut 18, and has a slot 20 through which a collared clamp screw 22 projects into the main frame, to hold it securely in adjusted position.

The slide 14 carries at its top a frame 24 on which is pivoted a table 26 on a horizontal axis 28. The table is angularly adjustable about the axis 28 by a screw 30 of finer thread than the screw 16, with a lock nut 32. The upper end of the screw 30 bears against the lower side of the table 26.

The table 26 has a slot 34 in it through which projects a rotary cutter 36, which is mounted on the shaft of a motor 38. The plane of the cutter is perpendicular to the axis 28. The frame 24 is slotted for the shaft, as shown at 39 in Fig. 2.

The table 26 has a groove 40 in its top (Figs. 1 and 3) extending from its edge into the slot 34. A rigid but soft (preferably brass) plate 42 is laid in this groove and fits loosely enough to be slid back and forth in it. The plate is a little thicker than the depth of the groove, as seen in Fig. 3.

A gage member 44 having a cross arm 46 is fastened to the table by bolt and slot connections 48, to permit the gage to be moved toward and from the cutter 36. When the gage member 44 is clamped down to the table 26, it binds the plate 42 firmly in place. The edge of the gage is perpendicular to the plane of the cutter.

When a new cutter is mounted in the machine, the table 26 is adjusted to proper position by the screws 16 and 30. The adjustment is secured roughly by the screw 16 and the finer screw 30 easily secures the exact amount of projection desired for the cutter. Thus, the table 26 can always be kept on the angle that is convenient for the operator. The gage 44 is then loosened enough to permit the plate 42 to move, and this plate is pushed into the cutter until the cutter has cut a notch into it of substantial depth. The gage is then adjusted to proper gaging position to secure the proper width of rim on the attaching face of the heel blank, and clamped in place by the devices at 48.

The operator then takes a heel blank 52, as shown in Fig. 9, in his fingers and places it on the table with its breast surface substantially parallel to the plane of the cutter and its edge against the gage. He then pushes and turns it successively through the positions shown in Figs. 4 to 8, and removes it from the machine, it then having the appearance shown in Fig. 10 at 54.

The plate 42 can be pushed in by a following plate of the same character, as it is cut away by successive adjustments, and used up to its last inch or so. It supports the edge of the heel block immediately adjacent to the ends of the cutter teeth and prevents tearing out any portion of the heel blank rim by the cutter.

Having described my invention, what I claim as new and desire to secure by Letters Patent of the United States is:

1. In a wood heel concaving machine, a work table, a rotary concaving cutter, and a guard plate carried by the table, said plate being made of a rigid material easily cut by the cutter, and being also movable on the table toward the cutter to permit the cutter to cut a slot in the guard plate closely surrounding the effective portion of the cutter.

2. In a wood heel concaving machine, a work table, a rotary cutter, a guard plate mounted on the upper surface of the table and having a notch in its end closely surrounding the operative portion of the cutter, and an adjustable gage mounted on the table and arranged to clamp the guard plate in operative position when fastened in gaging position.

3. In a wood heel concaving machine, a work table having a slot extending through it, a rotary cutter projecting through the slot, a guard plate mounted on the upper surface of the table and having a notch in its end closely surrounding the operative portion of the cutter, and an adjustable gage mounted on the table and arranged to clamp the guard plate in operative position when fastened in gaging position.

4. In a wood heel concaving machine, a work table having a slot extending through it, a rotary cutter projecting through the slot, the table having also a groove in its upper surface extending into the slot, a guard plate in the groove, with a notch in its end surrounding the operative portion of the cutter, the thickness of the guard plate being greater than the depth of the groove, a gage member resting on the guard plate adjacent to the cutter, and means for fastening the gage member to the table.

5. In a wood heel concaving machine, a work table having a slot extending through it, a rotary cutter projecting through the slot, the table having also a groove in its upper surface extending into the slot, a guard plate in the groove, the guard plate being made of a rigid material substantially softer than the cutter, so that the guard plate may be pushed along the groove into engagement with the cutter to form a notch in the end of the guard plate closely surrounding the operative portion of the cutter, and a gage member adjustably mounted on the table above the guard plate and arranged to clamp the guard plate in position as the gage member is fastened in adjusted position.

In testimony whereof I have signed my name to this specification.

JOHN C. SHAMBOW.
